CONTROL MEANS FOR SEWING MACHINES

Edgar P. Turner, Fanwood, N. J., assignor to The Singer Manufacturing Company, Elizabeth, N. J., a corporation of New Jersey

Application May 5, 1950, Serial No. 160,271

16 Claims. (Cl. 112—98)

1

This invention relates to improvements in sewing machine control mechanisms, and more particularly in mechanisms for controlling the amplitude of lateral needle vibration of zigzag-stitch sewing machines, although certain features of construction are adapted for employment in controlling other sewing machine components such as presser-bars or stop-motion devices.

A more specific object of this invention is to provide an improved manually operable means for controlling the amplitude of needle-vibration of an organized pantograph-equipped embroidery machine of the type which is adapted for placing monograms on sheets, towels, garments and the like goods.

With the above and other specific objects in view, the invention comprises the devices, combinations and arrangements of parts hereinafter described in connection with the accompanying drawings which illustrate a preferred embodiment of the invention, from which the several features of the invention and the advantages attained thereby will be readily understood by those skilled in the art.

In the drawings:

Fig. 1 represents a perspective view of a sewing machine and its supporting table in which the present invention is employed.

Fig. 2 represents a fragmentary right-hand end view of the unit disclosed in Fig. 1.

Fig. 3 represents, in a diagrammatic manner, a monogram formed in a piece of work material by means of zigzag stitches.

Fig. 4 represents a front side elevation, partly in section, of a sewing machine employed with the present invention.

Fig. 5 represents a fragmentary rear side elevation of the sewing machine disclosed in Fig. 4 and with the rear bracket-arm wall cover-plate removed.

Fig. 6 represents, on an enlarged scale, a section of a portion of the machine bracket-arm taken substantially in the horizontal plane containing the needle-bar vibrating cam-shaft.

Fig. 7 represents a bottom plan view of the table unit which supports the sewing machine, which view is taken substantially along the line 7—7 of Fig. 2.

Fig. 8 represents a sectional view taken substantially along the line 8—8 of Fig. 7.

Fig. 9 represents a sectional view taken substantially along the line 9—9 of Fig. 7.

Fig. 10 represents a side elevational view of a portion of the present control apparatus.

Fig. 11 represents a right-hand end view of the control apparatus disclosed in Fig. 10.

2

Fig. 12 represents, on an enlarged scale, a diagrammatic showing of the various motions imparted to a portion of the control mechanism disclosed in Fig. 11.

Fig. 13 represents a fragmentary view of the under side of the table and illustrates an alternate form of needle-bar control means.

Referring to the drawings, the present invention is broadly employed with a zigzag type sewing machine 14 and a manually controlled pantograph mechanism 15 of which one end portion carries an embroidery hoop 16 for presenting beneath the vibrating needle of the sewing machine the work to be monogrammed. The other end

portion of the pantograph mechanism carries a stylus, generally designated by the numeral 17, which the operator employs for tracing a monogram stencil or pattern which may be presented beneath the pantograph. The movements of the embroidery hoop are directly controlled by the operator through the pantograph and thus the monogram formed in the work by the sewing machine corresponds to the stencil or pattern. For a more detailed description of a related type pantograph and sewing machine unit, reference may

be had to the U. S. Patent of Corrall No. 1,328,821, January 27, 1920. A knee-shift lever 18 is provided for enabling the operator to vary the amplitude of lateral needle vibration so that the

width of the zigzag seam may be altered during the stitching operation to the end that the monogrammed outline may be of divers widths.

Referring particularly to Figs. 1, 2 and 7, the present invention is incorporated in a table having a substantially flat upper surface 19 which is provided at one end portion with a conventional sewing machine cut-out 20 for receiving therein the above noted zigzag sewing machine generally designated by the numeral 14. This cut-out, and

consequently the sewing head, may be set at an angle of 45° with the longitudinal axis of the table in order that the vertical and horizontal runs of the monogrammed work will have the same angle of stitches. In this connection, reference may be

had to Fig. 3 wherein a monogram in the form of a letter L is disclosed and designated by the numeral 21. This monogram is formed by means of zigzag stitches 21', and it will be understood that with the machine head 14 disposed at the

above noted 45° angle, the vertical and horizontal runs of the monogrammed work have the same angle of stitches. For the purpose of illustration, the distance between these stitches is greatly exaggerated. Mounted directly beneath the table top 19 and upon a shelf 22 carried by table legs 23 is a horizontally disposed pantograph-support-

ing apron 24 which extends outwardly from beneath the table top 19 in order to expose the stylus-supporting end of the pantograph unit. This stylus-supporting end of the pantograph mechanism is supported directly upon the outwardly protruding apron 24 while the other end portion thereof is carried by the shelf 22 at a location beneath the table level and in vertical alignment with an opening 25 formed within the table surface. An arm 26 extends upwardly from the pantograph and through this table opening and it is provided with a horizontal limb 27 which extends over the table 19 so as to support the embroidery hoop 16 directly over the sewing machine throat-plate and beneath the needle-bar mechanism.

The upper surface 28 of the protruding apron 24 may be formed from a flat piece of transparent material directly beneath which and in a rectangular pocket 29 formed in the apron 24, a pattern or stencil sheet may be positioned. The stylus 17 provided on the outwardly protruding end portion of the pantograph may be tracked about a given pattern carried in the apron pocket 29 so as to effect a corresponding movement of the embroidery hoop 16 to the end that the sewing machine will produce a monogram of predetermined shape.

The above noted protruding apron 24 is slidably mounted on track elements 30 carried directly upon the shelf 22 so that it may be manually shifted crosswise of the table. This movement of the apron, which carries the stylus-supporting end of the pantograph, is effective to alter the pattern-to-monogram ratio. An apertured indexing plate, generally designated by the numeral 31, is provided at the right-hand end portion of the apron and a manually operable locking pin 32 is provided upon the shelf 22 for the purpose of locking the plate 31 and consequently the apron 24, in any one of several predetermined apron positions. Means, not herein disclosed, are provided in each of the two end portions of the pantograph unit for locking such ends respectively to the apron and to the shelf, thereby to effect a relative adjustment of the two pantograph ends upon the shifting of the apron. The specific construction details of the apron 24, together with the pantograph unit 15 are not a part of the present invention and thus need not be described in detail.

The above noted sewing machine 14 comprises a flat bed 33 affording a work-support, and from one end of which rises the hollow standard 34 of a bracket-arm 35 overhanging the bed-plate and terminating in a head 36 closed at its outer end by a detachable face-plate 37.

Referring particularly to Figs. 4, 5 and 6, there is rotatably journaled in suitable bearings provided in the bracket-arm 35 a horizontally disposed main-shaft 38 extending lengthwise of the bracket-arm and carrying at one end a driving pulley 39. At its other end the main-shaft carries a counterbalanced crank 40 provided with a crank-pin 41 upon which is pivotally mounted a split sleeve 42 having depending spaced ears 43 between which the upper end of a needle bar reciprocating link 44 is pivotally mounted for swinging movements about an axis transverse to the axis of the main-shaft 38. The lower end portion of the link is pivoted between the upstanding spaced ears 45 of a sleeve 46 journaled upon a stud 47 extending parallel to the main-shaft 38 from a collar 48 suitably secured upon a vertically disposed needle-bar 49.

The needle-bar 49 carries at its lower end a needle 50 and is journaled for endwise reciprocation in suitable bearings provided upon a vibratory gate 51. The flattened upper end of the gate is disposed within the vertically slotted lower end of a supporting member 52 carried by the head 36. Thus, the gate is pivotally mounted in the usual fashion for swinging about a pivotal axis substantially transverse to the axis of rotation of the main-shaft 38. The lower end of the gate 51 is slabbed so as to provide opposed flat walls 53 slidably disposed within appropriate guide walls formed in the slotted lower wall of the bracket-head 36, which construction confines the swinging movements of the gate 51 in a vertical plane which in the present case also contains the axis of rotation of the shaft 38.

Extending horizontally from the lower end of the vibratory gate 51 is an arm 54 of which the free end at the side of the bracket-arm head carries a pivot block 55. Embracing the pivot block 55 is the forked end of a rock-arm 56 depending from the front end of a short rock-shaft 57 disposed horizontally transverse to the main shaft 38 and suitably journaled at the under side of the bracket-arm head 36. Extending upwardly from the rock-shaft 57 at the rearward side of the head 36 is a rock-arm 58 of which the free end is connected by a pivot screw 59 to one end of a pitman 60 disposed horizontally and extending at the rearward side of the bracket-arm 35. The other end of the pitman 60 has a fork or yoke 61 and extends through a slot or opening 62 formed at the outward side of the rear wall of the bracket-arm. It will be understood that the yoked end of the pitman is disposed extending rearwardly of the bracket-arm wall. A cover-plate 63 may be employed for enclosing the forked end of the pitman 60. The yoke 61 of the pitman embraces a cam 64 disposed within the bracket-arm recess. This cam 64 has a flange 65 between which the pitman is laterally confined. The cam 64 is suitably secured upon the rearward end of the cam-shaft 66 journaled within the front and rear walls of the bracket-arm 35. A shaft collar 67 housed in a recess 68 in the front side of the bracket-arm confines the cam shaft 66 against endwise movement. A spiral gear 69 carried by the main-shaft drives a spiral gear 70 upon the cam shaft 66, whereby the latter is rotated at one-half the speed of rotation of the main-shaft 38. From the foregoing, it will be understood that during the operation of the machine, the cam 64 vibrates the pitman 60 laterally about its pivot screw 59 and that the needle 50 performs one complete reciprocation for each direction of lateral throw of the pitman.

In order to translate the otherwise idle lateral vibratory movements of the pitman 60 into effective endwise reciprocatory movements thereby to impart swinging movements to the needle-bar gate 51, a guide roller 71 is suitably secured upon the pitman at its inner side and adjacent the yoke member. The guide roller 71 is received within a guideway 72 constituted by the rearwardly opening slot formed in the latter or rearward exposed face or guide head 73 extending into the bracket-arm 35. The guideway is segmental, the center of curvature thereof in one position of the guide head 73 lying in the pivotal axis of the pitman 60 afforded by its pivotal connection with the rock-arm 58.

The guide head 73 has a hub 74 extending through an aperture 75 in the bottom wall of the bracket-arm cavity, said hub being secured by a

set screw 74' upon an adjusting shaft 76 disposed parallel to the cam-shaft 66 and having the longitudinal axis in substantially the horizontal plane containing the axis of rotation of the cam shaft. The guide head hub 74 abuts against the end of a bearing bushing 78 suitably secured in the front wall of the bracket-arm 35 and affording a bearing for the adjusting shaft 76. Secured by screw 79 upon the adjusting shaft 76 is a manually operable member 80 in the form of a lever arm. The throw of the arm 80 is limited in one direction by a stop screw 81 adjustably secured within an apertured ear 82 mounted directly upon the bracket-standard 34 to locate the guide head in its zero position so as to position the guide head in a manner whereby the guideway 72 is concentric to the pivot screw of the pitman 61. Thus, the pitman may perform idle lateral vibrations and the needle-bar gate 51 will remain stationary during the operation of the machine. Movement of the lever 80 from its zero position is adjustably limited by an opposed stop screw 83 threaded into another ear 84 also carried upon the bracket-arm 35. It will be understood that when the lever 80 is moved from its zero position toward the stop screw 83, the guide head is angularly adjusted into position such that, during the operation of the machine, the travel of the guide roller 71 in the guideway 72 effects endwise reciprocation of the pitman 61, thereby imparting lateral vibratory movements to the needle-bar gate 51. A coil spring 85 has its upper end secured to the lever 80 for biasing the latter into engagement with the lower stop screw 81 while the lower end portion of the spring is secured to the bracket-arm as by a pin 85'. Thus, the spring urges the needle-bar control mechanism into a null position so that the needle-bar will reciprocate in a fixed vertical path.

The above noted knee-shift lever 18 is in the form of a substantially inverted L-shaped crank, the horizontal limb 86 of which is journaled within a pair of apertured brackets 87 and 88 which are respectively secured directly to the adjustable apron 24 and to the shelf 22. Also mounted on the apron 24 is a substantially U-shaped bracket 89 which, as may be best observed from Fig. 2, functions to embrace a portion of the knee-shift lever so as to prevent the latter from shifting endwise within its journal bracket 87. This lever 18 is adapted to be operated by an operator's knee.

Referring particularly to Figs. 1, 4, 7 and 8, the free end portion of the lever arm 80 has pivotally connected thereto the upper end portion of an extension arm 90 the lower end portion of which extends through an aperture 91 provided in the sewing machine bed-plate 33 so as to permit its extreme lower end portion to project below the surface of the table. Means hereinafter described are provided for connecting the lower end portion of the member 90 to the knee-shift lever. Thus, the operator may vary the amplitude of the lateral needle vibration during the operation of the machine by means of the knee-shift lever 18 to the end that the width of the zigzag seams may be altered. In this connection, reference may be had to Fig. 3 wherein a monogram is illustrated as a letter L. It will be observed that the width of this letter varies throughout its length so that in order properly to form such a letter by means of stitches it will be necessary to vary the amplitude of lateral needle vibration. Thus, the present invention contemplates the provision of a mechanism which may be controlled by the above noted knee-shift lever 18 so

that a movement of such lever will vary the amplitude of lateral needle vibration.

As hereinabove noted, the operator may vary the pattern-to-monogram ratio by shifting the apron 24 relative to the shelf unit 22. This movement of the apron also varies the knee-shift linkage system so that the ratio of movement of the knee-shift lever 18 relative to that of the needle control lever 80 may be altered and the maximum throw of the needle is made to vary with the monogram size while the knee-shift lever is still adapted to be moved in accordance with the pattern size.

More specifically, the present knee-shift linkage system comprises a horizontally disposed shaft 92, the opposite end portions of which are journaled in the end portions of a box-like bracket generally designated by the numeral 93. Referring particularly to Figs. 2 and 7, this bracket 93 may be secured to the upper leg channel member 94 by means of bolts 95, 95. It is to be understood that the shaft 92 is disposed in parallelism with the knee-shift lever 86. Carried at the opposite end portions of the shaft 92 are a pair of arms of unequal length which are connected together at their free end portions by means of a rod 96 which overlies and engages a crank-arm 97 carried by the horizontal limb 86 of the knee-shift lever. The shorter of these two arms is designated by the numeral 98 while the larger one is designated by the numeral 99. Thus, in effect, the arms 98 and 99, together with the inclined rod 96, form a crank which engages the crank 97 so as to transmit motion from the knee-shift lever 18 to the shaft 92. Furthermore, the rod 96 forms a substantially inclined cam portion of this crank so that when the knee-shift lever 18 is rotated relative thereto the effective lever arm ratios between such cranks will be varied. Referring particularly to Figs. 10, 11 and 13, it is to be understood that the short arm 98 is provided with a crank element 100 which, in one form of the present invention, is adapted to underlie directly the lower end portion of the depending connecting element 90. The above noted coil spring 85 functions to bias the lever 80 together with the connecting element 90 downwardly thereby to force the lower end portion of the element 90 into operable engagement with the underlying crank 100. Furthermore, a spring 101 embracing the rear end portion of the knee-shift lever 86 functions to bias this lever about its longitudinal axis and in a clockwise direction as viewed in Fig. 1. More specifically, one end portion of this spring is secured by means of a pin 102 to the knee-shift lever 86 while the other end portion 103 embraces the bracket 88 so as to bias the lever arm 86 in the clockwise direction.

The inclined rod 96, carried by the two depending arms 98 and 99 forms, as above noted, an angle with the knee-shift lever 86 and thus when the apron 24 is shifted relative to the shelf 22 the crank arm 97 and the rod 96 are moved relative to each other to the end that their effective lever ratios are varied. Thus, an increment of movement of the knee-shift lever 86 about its longitudinal axis can produce various increments of movement in the depending connection element 90 depending upon the amount of lengthwise adjustment of the knee-shift lever arm 86 relative to the inclined rod 96. From the above, it will be appreciated that a rotary movement of the knee-shift lever 86 about its longitudinal axis from its zero position will be effec-

tive to operate the above noted lever arm 80 which, in turn, functions to control the amplitude of lateral needle vibrations. As the movement of the knee-shift lever arm 86 is increased in a counterclockwise direction as viewed in Fig. 1, the lever arm 80 will be shifted also in a counterclockwise direction so as to increase the amplitude of lateral needle-bar vibrations from zero to a maximum. Also, if the knee-shift lever 86 is moved endwise of itself it will function to alter the effective lever ratio between its crank portion 97 and the inclined rod 96 so that a given amplitude of rotary motion of the knee-shift lever will produce various selective amplitudes of lateral needle bar vibration.

For a more complete understanding of this adjustable linkage system, reference may be had to Figs. 10, 11 and 12. Referring first to Fig. 11, the solid lines illustrate the knee-shift lever 86 in its null or zero position while the dotted lines illustrate this member in its maximum position of rotary movement. It will be noted that this rotary movement of the lever arm will produce a corresponding rotary movement of the crank 100 which functions to lift the depending connecting element 90 which projects through the supporting table (see Fig. 13). Also, Fig. 11 illustrates the arm 98 as having a single aperture 104 for receiving the headed end of the rod 96 while the arm 99 is provided with a plurality of apertures 105 for receiving the other end of the rod. Thus, the rod 96 may have its lower end portion inserted in any one of the several apertures 105 to the end that its angle relative to its axis of rotation may be selectively varied.

Referring particularly to Fig. 12, there is illustrated diagrammatically the effect which the lengthwise adjustment of the lever arm 86 has upon the movements of the crank element 100. The solid lines illustrate the member 97 in its zero position while the dotted lines represent this member at the end portion of a given amplitude of motion. Also illustrated in this view is the rod 96 which, when the crank 97 is turned through a given amplitude to a position represented by the dotted lines, moves through an angle A to a secondary position designated by the dotted circle 96'. However, if the lever arm crank 86 is shifted to a dotted position as illustrated in Fig. 10 then the crank 97 will function to shift the rod 96 through angle B, which latter angle is appreciably greater than the angle A. The initial and final positions of the rod 96 when moved through angle B are designated by the dotted circles designated respectively by the numerals 96'' and 96''''. From this it will be readily appreciated that by shifting the knee-shift lever 86 lengthwise of itself an adjustment in the linkage system will be effected whereby a given amplitude of rotary motion of the knee-shift lever may be made to produce various selective amplitudes of motion within the crank 100.

As hereinabove noted, the first form of the present invention contemplates the provision of a table top which is provided at one end portion with a cut-out 20 formed at 45° to the longitudinal axis of the table. This cut-out and, consequently, the sewing head, are set at this 45° so that the vertical and horizontal runs of the monogram work will have the same angle of stitches. Experiments with this type of unit indicate that unless relative rotation between the work and the sewing head can be produced about the null or vertical axis of the sewing needle, many styles of monogram letters cannot be properly produced. In other words, to produce a

proper monogram in some instances it is necessary to have the direction of the sidewise needle vibrations disposed at a substantial angle to the longitudinal axis of each limb of a monogram letter. In view of this situation, a second form of the present invention contemplates the provision of means whereby the sewing machine head may be rotated about the null axis of its needle.

More specifically, and referring particularly to Figs. 1, 7 and 8, the top of the present table 19 may be provided with a circular aperture 105 in which is rotatably mounted, in any suitable manner, a turntable 106 having a cut-out 20 for receiving therein the sewing head 14. Projecting upwardly from the turntable platform 106 at a location adjacent the work-supporting end of the sewing machine is a handle 108 by means of which an operator may swing the turntable and head into any desired angular location relative to the work. The cut-out 105 is so located within the turntable that the null or vertical axis of the needle corresponds with the center of rotation of the turntable.

This second form of the invention necessitates an alteration in the variable needle throw control mechanism described hereinabove. Due to the fact that the machine sewing head is turnable about its vertical needle axis, provision has to be made for properly transmitting the motions of the knee-shift lever, which is carried upon the stationary table unit, to the needle throw adjusting lever 80 which is carried upon the rotatable sewing head.

In the second form of this invention shown in Figs. 7, 8 and 9, this motion-transmitting system comprises two horizontally disposed interengaging fulcrum levers 109 and 110. The first of these levers is provided with a transverse shaft element 111 which is pivotally mounted in brackets 112, 112 secured directly to the turntable so that the member 109 is bodily rotatable with the turntable. In this form of the invention, the free end portion of the fulcrum lever 109 is disposed directly beneath the lower end portion of the connecting element 90 so as to be engageable therewith. Also, the fulcrum lever 109 is disposed lengthwise of the sewing head so that its intermediate portion intersects the null axis of the needle, which null axis is designated by the numeral 113.

The second fulcrum lever 110 is also provided with a short transverse shaft 114 which is pivotally mounted in brackets 115, 115 secured directly to the under surface of the table 19. This second fulcrum member is disposed so that the intermediate portion thereof will intersect the null axis 113 of the needle and underlie and engage an intermediate portion of the member 109. The free end portion of the fulcrum lever 110 is engaged and supported by a crank element 100' which is secured directly to the arm 99 of the adjustable crank system. In other words, the crank 100 employed in the first form of the invention is eliminated and in lieu thereof the crank 100' is provided in its place.

From the above, it will be understood that rotary movements of the knee-shift lever 86 will be imparted to the crank arm 100' through the above described adjustable crank system and these movements will be faithfully transmitted to the depending link 90 by means of the interengaging fulcrum levers 109 and 110. Clearly, any rotation of the sewing head 14 and the platform 106 about the null axis 113 will not disturb the effec-

tiveness of this motion-transmitting system. Thus, an operator may, by operating the knee-shift lever about its pivotal axis, vary the throw of the needle during the operation of the machine to the end that the width of the zigzag seams may be altered. Furthermore, by shifting the knee-shift lever lengthwise of its axis of rotation, the operator will effect a change in the ratio of the rotary knee-shift movement relative to that of the needle throw control lever 80 so that a predetermined amplitude of rotary knee-shift lever movement will produce various selective amplitudes of movement of the needle control lever 80.

In order to form a proper foundation for the terminology employed in the accompanying claims, we hereby state that the present invention broadly provides a sewing machine operative mechanism, such as a needle vibrating mechanism, and manipulative means for controlling the action of the operative mechanism and including (1) an element 80 which is adapted to be selectively actuated through various amplitudes of movement for thus controlling the operative mechanism, (2) means including a manually operable lever arm 18 for actuating the element 80, and (3) manually controlled adjustable means such as the inner engaging motion transmitting cranks 96 and 97, operatively connecting the lever arm 18 with the element 80 whereby a predetermined amplitude of movement of the lever arm 18 can be selectively made to produce various amplitudes of movement of the element 80. The manually operable lever arm 18 also functions as a manually operable means for adjusting the cranks 96 and 97 relative to each other so as to alter the effective lever ratio therebetween.

Having thus set forth the nature of the invention, what I claim herein is:

1. A sewing machine having operative mechanism carried thereby, manipulative means for controlling the action of said operative mechanism and including an element which is adapted to be selectively actuated through various amplitudes of movement for thus controlling said operative mechanism, means including a manually operable lever arm for actuating said element, and manually controlled adjustable means operatively connecting said lever arm with said element whereby a predetermined amplitude of movement of said lever arm can be selectively made to produce various amplitudes of movement of said element, said adjustable means including a pair of interengaging motion-transmitting cranks of which one is mounted for independent adjustable movement relative to the other whereby such adjustment will alter the effective lever ratio therebetween, and manually operable means for so adjusting said adjustable crank.

2. A sewing machine having operative mechanism carried thereby, manipulative means for controlling the action of said operative mechanism and including an element which is adapted to be selectively actuated through various amplitudes of movement for thus controlling said operative mechanism, means including manually operable lever arm for actuating said element, and manually controlled adjustable means operatively connecting said lever arm with said element whereby a predetermined amplitude of movement of said lever arm can be selectively made to produce various amplitudes of movement of said element, said adjustable means including a pair of interengaging motion-transmitting cranks each being turnable about a fixed

axis of rotation and one having its surface of crank engagement inclined relative to its axis of rotation whereby a relative adjustment of said cranks lengthwise of their axes will alter their effective lever ratios, and means for adjusting one of said cranks relative to the other lengthwise of its axis of rotation.

3. A sewing machine having operative mechanism carried thereby, manipulative means for controlling the action of said operative mechanism and including an element which is adapted to be selectively actuated through various amplitudes of movement for thus controlling said operative mechanism, means including a manually operable lever arm for actuating said element, said lever arm being mounted for rotation about and movement lengthwise of a predetermined axis, and manually controlled adjustable means operatively connecting said lever arm with said element whereby a predetermined amplitude of rotary movement of said lever arm can be selectively made to produce various amplitudes of movement of said element, said adjustable means including a pair of interengaging motion-transmitting cranks each being turnable about a fixed axis of rotation and one having its surface of crank engagement inclined relative to its axis of rotation whereby a relative adjustment of said cranks lengthwise of their axes will alter their effective lever ratios, and means connecting one of said cranks with said lever arm whereby such crank will be both rotated about and shifted lengthwise of its axis of rotation in synchronism with the like movements of said lever arm.

4. A sewing machine having, an endwise reciprocatory and laterally vibratory needle, automatic means for reciprocating said needle endwise of itself, automatic means for laterally vibrating said needle, means for selectively varying the amplitude of lateral needle vibration including a pair of interengaging motion-transmitting elements of which one is mounted for independent adjustable movement relative to the other whereby an adjustment of such adjustable element will alter the amplitude of motion transmitted from one of such elements to the other, and a manually controlled member shiftable in a first direction for operating said interengaging elements thereby to alter the amplitude of lateral needle-bar vibration and being shiftable in a second direction to adjust said interengageable elements relative to each other.

5. A sewing machine having, an endwise reciprocatory and laterally vibratory needle, automatic means for reciprocating said needle endwise of itself, automatic means for laterally vibrating said needle, means for selectively varying the amplitude of lateral needle vibration including a pair of interengaging motion-transmitting elements of which one is mounted for independent adjustable movement relative to the other whereby an adjustment of such adjustable element relative to its associated element will alter the amplitude of motion transmitted from one of such elements to the other, a manually controlled member connected to one of said elements for actuating the same thereby selectively to vary the lateral needle vibration, and manually controlled means for effecting an adjustment of said adjustable element relative to its associated element thereby to cause a predetermined amplitude of movement of said member to produce various selective amplitudes of lateral needle vibration.

6. A sewing machine having, an endwise reciprocatory and laterally vibratory needle, automatic means for reciprocating said needle endwise of itself, automatic means for laterally vibrating said needle, means for selectively varying the amplitude of lateral needle vibration including a pair of interengaging motion-transmitting cranks of which one is mounted for independent adjustable movement relative to the other whereby an adjustment of such adjustable crank relative to its associated crank will alter the effective lever ratios therebetween, a manually controlled member connected to one of said cranks for actuating the same thereby selectively to vary the lateral needle vibration, and manually controlled means for effecting an adjustment of said adjustable crank relative to its associated element thereby to cause a predetermined amplitude of movement of said member to produce various selective amplitudes of lateral needle vibration.

7. A sewing machine having, an endwise reciprocatory and laterally vibratory needle, automatic means for reciprocating said needle endwise of itself, automatic means for laterally vibrating said needle, means for selectively varying the amplitude of lateral needle vibration including a pair of interengaging motion-transmitting cranks each being turnable about a fixed axis of rotation and one having its surface of crank engagement inclined relative to its axis of rotation whereby a relative adjustment of said cranks lengthwise of their axes will alter their effective lever ratios, a manually controlled member connected to one of said cranks for turning the same about its axis thereby selectively to vary the lateral needle vibration, and manually controlled means for effecting a relative adjustment of said cranks lengthwise of their axes thereby to cause a predetermined amplitude of movement of said member to produce various selective amplitudes of lateral needle vibration.

8. A sewing machine having, an endwise reciprocatory and laterally vibratory needle, automatic means for reciprocating said needle endwise of itself, automatic means for laterally vibrating said needle, means for selectively varying the amplitude of lateral needle vibration including a pair of interengaging motion-transmitting cranks each being turnable about a fixed axis of rotation and one having its surface of crank engagement inclined relative to its axis of rotation whereby a relative adjustment of said cranks lengthwise of their axes will alter their effective lever ratios, and a manually controlled member connected to one of said cranks for turning the same about its axis thereby selectively to vary the lateral needle vibration, said manually controlled member being shiftable lengthwise of itself for effecting, in response to the lengthwise movement thereof, a relative adjustment of said cranks lengthwise of their axes thereby to cause a predetermined amplitude of rotary movement of said member to produce various selective amplitudes of lateral needle vibration.

9. The combination of a table, a sewing machine mounted upon said table and having an endwise reciprocatory and laterally vibratory needle, automatic means carried by the machine head for reciprocating said needle endwise of itself, automatic means carried by the machine head for laterally vibrating said needle, means for selectively varying the amplitude of lateral needle vibration including a pair of interengag-

ing motion-transmitting rotary cranks carried by and disposed beneath said table, one of said cranks being mounted for independent adjustable movement relative to the other whereby an adjustment of such adjustable crank relative to its associated crank will alter the degree of motion transmitted from one of such cranks to the other, means connecting a first of said cranks to the needle vibrating mechanism, a manually controlled member located beneath said table and connected to the second of said cranks for actuating the same thereby selectively to vary the lateral needle vibration, and manually controlled means for effecting an adjustment of said adjustable crank relative to its associated crank thereby to cause a predetermined amplitude of movement of said member to produce various selective amplitudes of lateral needle vibration.

10. The combination of a table, a sewing machine mounted upon said table and having an endwise reciprocatory and laterally vibratory needle, automatic means carried by the machine head for reciprocating said needle endwise of itself, automatic means carried by the machine head for laterally vibrating said needle, means for selectively varying the amplitude of lateral needle vibration including a pair of interengaging motion-transmitting cranks each being carried beneath the upper surface of said table and being turnable about a fixed axis of rotation and one having its surface of crank engagement inclined relative to its axis of rotation whereby relative adjustment of said cranks lengthwise of their axes will alter their effective lever ratios, means connecting a first one of said cranks to the needle vibrating means, and a knee-shift lever disposed beneath said table and connected to a second one of said cranks for turning the same about its axis of rotation thereby selectively to vary the lateral needle vibration, said knee-shift lever being shiftable lengthwise of itself for effecting, in response to the lengthwise movement thereof, a relative adjustment of said cranks lengthwise of their axes thereby to cause a predetermined amplitude of rotary movement of said knee-shift lever to produce various selective amplitudes of lateral needle vibration.

11. The combination of a table, a platform rotatably mounted upon said table, a sewing machine head carried upon said platform, operative mechanism carried by the sewing machine head, manipulative means for controlling the action of said operative mechanism and including an element extending from said head to a location beneath said platform, said element being disposed at one side of the axis of platform rotation so as to be rotatable thereabout, a manually operable lever arm pivotally mounted beneath the table surface, and means operatively connecting said element with said lever arm whereby a turning movement of the latter will function to actuate said element and thus control said operative mechanism, said last mentioned means including a fulcrum lever operatively connected with said element and pivotally mounted on said platform so as to be bodily rotatable therewith, and means including a crank member connected with said lever arm and engaging said fulcrum lever at a point located along the axis of platform rotation.

12. The combination of a table, a platform rotatably mounted upon said table, a sewing machine head carried upon said platform, operative mechanism carried by the sewing machine head, manipulative means for controlling the action of

said operative mechanism and including an element extending from said head to a location beneath said platform, said element being disposed at one side of the axis of platform rotation so as to be rotatable thereabout, a manually operable lever arm pivotally mounted beneath the table surface, and means operatively connecting said element with said lever arm whereby a turning movement of the latter will function to actuate said element and thus control said operative mechanism, said last mentioned means including a pair of interengaging fulcrum levers of which one is operatively connected with said element and pivotally mounted upon said platform so as to be bodily rotatable therewith while the other is operatively connected with said lever arm and pivotally mounted upon the table proper, said two fulcrum levers engaging each other at a point located along the axis of platform rotation.

13. The combination of a table, a platform rotatably mounted upon said table, a sewing machine head carried upon said platform, operative mechanism carried by the sewing machine head, manipulative means for controlling the action of said operative mechanism and including an element extending from said head to a location beneath said platform, said element being disposed at one side of the axis of platform rotation so as to be rotatable thereabout, a manually operable lever arm pivotally mounted beneath the table surface, and means operatively connecting said element with said lever arm whereby a turning movement of the latter will function to actuate said element and thus control said operative mechanism, said last mentioned means including a pair of interengaging fulcrum levers of which a first has its one end pivotally mounted upon said platform so that it is bodily rotatable with such platform while its other end portion is operatively connected with said element, the second of said fulcrum levers having its one end pivotally mounted upon said table while its other end portion is operatively connected with said lever arm, said two fulcrum levers engaging each other at a point located along the axis of platform rotation.

14. The combination of a table, a platform rotatably mounted upon said table, a sewing machine head carried upon said platform, operative mechanism carried by the sewing machine head, manipulative means for controlling the action of said operative mechanism and including an element extending from said head to a location beneath said platform, said element being disposed at one side of the axis of platform rotation so as to be rotatable thereabout, a manually operable lever arm pivotally mounted beneath the table surface, and means operatively connecting said element with said lever arm whereby a turning movement of the latter will function to actuate said element and thus control said operative mechanism, said last mentioned means including a pair of substantially horizontally disposed interengaging fulcrum levers of which a first has its one end pivotally mounted upon said platform so that it is bodily rotatable therewith

while its other end portion is operatively connected with said element, the second of said fulcrum levers being disposed beneath said first fulcrum lever and having its one end pivotally mounted upon said table, said two fulcrum levers engaging each other at a point located along the axis of platform rotation, and a crank element connected with said lever arm and underlying and engaging the free end portion of the second fulcrum lever.

15. The combination of a table, a platform rotatably mounted upon said table, a sewing machine head carried upon said platform, operative mechanism carried by the sewing machine head, manipulative means for controlling the action of said operative mechanism and including an element extending from said head to a location beneath said platform, said element being disposed at one side of the axis of platform rotation so as to be rotatable thereabout, a manually operable lever arm pivotally mounted beneath the table surface, and means operatively connecting said element with said lever arm whereby a turning movement of the latter will function to actuate said element and thus control said operative mechanism, said last mentioned means comprising a fulcrum lever operatively connected with said element and pivotally mounted on said platform so as to be bodily rotatable therewith, means including a crank member operatively connected with said lever arm and engaging said fulcrum lever at a point located along the axis of platform rotation, and means for varying the effective lever arm ratio between said lever arm and said crank member so that the ratio of movement between said lever arm and said element can be selectively varied.

16. A sewing machine having, an endwise reciprocatory and laterally vibratory needle, automatic means for reciprocating said needle endwise of itself, automatic means for laterally vibrating said needle, a manually controlled member connected with said last mentioned automatic means for selectively varying the amplitude of lateral needle vibration, a pair of interengaging motion-transmitting rotary cranks interposed between said last mentioned automatic means and said manually controlled member with one of said cranks being mounted for independent adjustable movement relative to the other whereby an adjustment of such adjustable crank will alter the amplitude of motion transmitted from one of such cranks to the other, and manually controlled means connected with said adjustable crank for effecting an adjustment thereof relative to the other of said cranks.
